UNITED STATES PATENT OFFICE

111,243

DESIGN FOR A MILK BOTTLE TRAY

James H. Everly, Wilmington, Calif.

Application July 6, 1937, Serial No. 70,270

Term of patent 14 years

To all whom it may concern:

Be it known that I, James H. Everly, a citizen of the United States, residing at 1206 McDonald Street, Wilmington, in the county of Los Angeles and State of California, have invented a new, original, and ornamental Design for a Milk Bottle Tray, of which the following is a specification, reference being had to the accompanying drawing, forming a part thereof.

Figure 1 is a top plan view of the tray showing my design.

Figure 2 is an end view of the same.

I claim:

The ornamental design for a milk bottle tray, as shown.

JAMES H. EVERLY.
